COTTON PICKER WITH AUTOMATIC POSITIONING MEANS

Clem Matthews, Jr., P.O. Box 41, Firebaugh, Calif.

Filed Sept. 15, 1958, Ser. No. 761,001

6 Claims. (Cl. 56—11)

This invention relates to mechanical cotton pickers and more particularly to automatic positioning means for the picker mechanisms of cotton pickers.

Conventional cotton pickers are provided with a manually operated control for raising and lowering the picker mechanism. With such a manual control, it has been found to be very difficult to operate the control to the position of the picker mechanism so that it is always in optimum picking position. This is particularly true where two row cotton pickers are utilized. Attempts have been made to solve the problem of properly raising and lowering the picker mechanism in Patents No. 2,674,075 and 2,700,857. However, such devices have not been completely satisfactory. They are quite complicated and are difficult to keep in adjustment. In particular, it has been found that excess pressure is often placed on the ground traversing shoes or plant lifters because of the cable mechanisms utilized in the devices.

In general, it is the object of this invention to provide automatic positioning means for a cotton picker which overcomes the above named disadvantages.

Another object of the invention is to provide automatic positioning means of the above character which serves to automatically raise and lower the picker mechanism to maintain it in optimum picking position.

Another object of the invention is to provide automatic positioning means of the above character which amplifies operation of the cotton picker.

Another object of the invention is to provide automatic positioning means of the above character which does not interfere with the conventional manual control for the cotton picker.

Another object of the invention is to provide automatic positioning means of the above character which provides either automatic or manual control.

Another object of the invention is to provide automatic positioning means of the above character which can be placed in automatic or manual control by the operation of a single control lever.

Another object of the invention is to provide automatic positioning means which provides positive action.

Another object of the invention is to provide automatic positioning means of the above character which eliminates the use of complicated linkages and otherwise simplifies the control.

Another object of the invention is to provide automatic positioning means of the above character which is particularly adapted for two-row cotton pickers.

Additional objects and features of the invention will appear from the preferred embodiment which is shown in detail in the accompanying drawings.

Referring to the drawing:

Figure 1 is a side elevational view with certain portions broken away and with certain portions shown in schematic form of a portion of a cotton picker with automatic positioning means incorporating the present invention.

2

Figure 2 is a top plan view looking along the line 2—2 of Figure 1.

Figure 3 is an enlarged front elevational view looking along the line 3—3 of Figure 1.

5 Figure 4 is a schematic diagram of the hydraulic system.

In general the present invention consists of automatic positioning means for raising and lowering the picker mechanism to maintain the picker mechanism in optimum picking position. A control valve is connected in the hydraulic system and is mounted on the front of the picker mechanism. The control valve is actuated by movement of the ground traversing plant lifters so that the picker mechanism is automatically positioned in accordance with the terrain encountered by the plant lifters.

10 As shown in the drawing, the conventional cotton picker includes one or more picker mechanism 11 depending upon whether or not the cotton picker is a single row or a two row cotton picker. Normally one picker mechanism is provided for each row. The picker mechanism as shown particularly in Patent No. 2,700,857 is normally mounted on a vehicle (not shown) for moving the picker mechanism over the cotton plants for removing the bolls of cotton. The picker mechanism is mounted on the 15 vehicle for vertical movement with respect to the vehicle so that it can be placed in optimum picking position with respect to the cotton plants and the ground being traversed.

20 Suitable means 12 is provided for each of the picker mechanisms to vertically move the picker mechanism and consists of an L-shaped crank arm 13 which is pivoted at 14. One end of the arm is pivotally connected to the picker mechanism at 16 and the other end is connected to a plunger 18 of a single acting hydraulic ram 19. As 25 hydraulic fluid is forced into the ram 19, the picker mechanism 11 is raised and when fluid is released from the hydraulic ram 19, the picker mechanism is lowered because of the weight of the picker mechanism.

30 The picker mechanism 11 is substantially conventional and for that reason will not be described in detail.

35 Ground traversing means 21 in the form of a pair of plant lifters 22 and 23 are mounted on each of the picker mechanisms for movement vertically of the picker mechanisms. Such plant lifters are normally provided to lift the lower most branches of the cotton plant preparatory to the picking operation by the picker mechanism 11. However, these plant lifters 22 and 23 in the present invention serve an additional function as hereinafter described. Each of the plant lifters is connected to the 40 picker mechanism by a parallelogram assembly 24 of a type well known to those skilled in the art to permit substantially rectilinear movement of the plant lifters. Each of the plant lifters is provided with a shoe 26 which is adapted to engage and slide over the ground. Plant lifter rods 27 are secured to each of the plant lifters 22 and 23 and extend forward of the picker mechanism. They slide over the ground and serve to gauge the contour or soil elevation over which the picker mechanism will pass. A spring 28 is provided with each of the plant lifters 22 and 23 to counterbalance the weight of the plant lifter so that the plant lifters will be more responsive to changes in contour of the soil. This counterbalancing also serves to prevent the plant lifters from digging into the soil.

45 The structure thus far described is substantially conventional and constitutes an operational environment with which the automatic positioning means of the present invention functions.

50 A front mounting plate 31 is provided on each of the picker mechanisms 11 and can be mounted thereon in any suitable manner such as by bolts 32 as shown in the drawing.

55 The mounting plate is provided with a recess 30 in

which is mounted a hydraulic control valve 33 which is termed an automatic control valve. The control valve 33 is provided with an actuating plunger 34 which is pivotally connected to an operating lever 36, the fulcrum of which is provided at 35.

The operating lever 36 is provided with extensions or portions 36a and 36b. The portions 36a and 36b engage operating rods 37 and 38 which are slidably accommodated in sleeves 39 and 41 affixed to the front mounting plate. The operating rods 37 and 38 are threaded into clevises 42 and 43. The clevises 42 and 43 are pivotally connected to arms 44 and 46 which are mounted on and rotate with rods 47 and 48. The rod 47 is rotatably mounted in bearings 49 and 51 and the rod 48 is rotatably mounted in a bearing 52. The opposite ends of the rods 47 and 48 are provided with arms 53 and 54 which are pivotally connected to connecting linkages 56 which serve to connect the arms 53 and 54 to the plant lifters 22 and 23.

Each of the connecting mechanisms is substantially identical and consists of a connecting rod 57 which is provided with a tubular portion 58 in which one end of a rod 59, pivotally connected to the associated plant lifter, is adapted to reciprocate. A spring 61 is mounted on the rod 59 between the tubular portion 58 and a collar 62 and normally serves to urge the rod 59 out of the tubular member 58 and to urge the plant lifter downwardly. By adjusting the position of the collar 62, the effective length of the rod 59 can be increased or decreased. When the rod 59 is lengthened the clearance of the picker mechanism with respect to the ground will be increased and when the rod 59 is shortened the converse will be true.

Additional means is provided for positively urging the automatic control valve 33 to one position and also at the same time to urge the plant lifters into a ground engaging position. Such means as shown consists of a spring 63 which has one end connected to the lever 36 at 64 and has the other end connected to the front mounting plate 31 through a projection 66. A nut 67 is provided for adjusting the tension on the spring 63 to regulate the pressure exerted by the plant lifters against the surface of the soil.

Although only one picker mechanism of the two row cotton picker has been shown and described the other picker mechanisms and the associated control means is identical to that hereinbefore described.

The hydraulic system utilized is shown in schematic form in Figure 4. The two picker mechanisms 11 of the cotton picker are adapted to be raised and lowered by the two hydraulic rams 19 shown in Figure 4, the upper hydraulic ram being for the right picker mechanism and the lower hydraulic ram being for the left picker mechanism. Two automatic control valves 33 are also provided, each of which is mounted on the associated picker mechanism in the manner hereinbefore described.

The hydraulic system also includes a tank or reservoir 66 which is connected by piping 67 to a pump 68. The pump 68 is connected to the reservoir 66 through a relief valve 69 and piping 71. The pump 68 is also connected to a T 72 by piping 73. One leg of the T 72 is connected to a manually controlled dual control valve 74 consisting of sections 76 and 77 by piping 78. Each of the sections 76 and 77 is provided with a valve member 79 which is adapted to be moved by an operating handle 81. The valves as shown in schematic form are provided with ports 82, 83 and 84 in the valve member. Section 76 of the dual valve 74 is connected to a T 86 by piping 87. One leg of the T 86 is connected to the hydraulic ram 19 for the left picker mechanism by piping 88. The section is also connected to a manual to automatic control valve 89 by piping 91. Piping 92 connects the control valve 89 to the reservoir 66. The control valve 89 includes a valve member 93 which is operated through an

operating handle 94. The valve member is provided with a port 96.

Section 77 of the dual valve 74 is connected to a T 97 by piping 98. One leg of the T is connected to the hydraulic ram 19 for the right hand picker mechanism of the cotton picker by piping 99. The section 77 of the dual control valve 74 is also connected to the return piping 91 by the piping 101.

The automatic control valves 33 consist of valve members 102 which are provided with ports 103, 104 and 105. The valve 33 for the left hand picker mechanism is connected to the T 86 by piping 106. The left hand valve 33 is connected to the right hand valve by piping 107. The left hand valve is connected to one side of a one-way check valve 110 by piping 108 and the other side of the check valve 110 is connected to one of the legs of the T 72 by piping 109.

The right hand valve 33 is connected to one of the legs of the T 97 by piping 111. It is also connected to the control valve 89 by piping 112. The dual control valve 89 is connected to a T 113 in the line 92 by piping 114.

A description of the operation of my automatic positioning means for the cotton picker mechanisms of a two row cotton picker may now be briefly described as follows: To facilitate the operation of the cotton picker, let the control valve 74 be called the manual control valve, the valves 33 be called the automatic control valve and the control valve 89 be called the manual to automatic control valve. Let it be assumed that all of the valves are in the positions shown in the drawing. In the position shown the manual to automatic control valve 89 is in the manual position and therefore the raising and lowering of the picker mechanisms will be under the control of the operating levers 81 of the dual control valve 74. With the operating levers 81 in the position shown, fluid will be pumped by the pump 68 through the piping 73 and the piping 78 into both sections of the control valve 74 after which it will pass through the ports 84, through the return piping 91 through the port 96 of the manual to automatic control valve 89 to the reservoir 66.

If the operating lever 81 of the section 76 is moved to the right as viewed in Figure 4, port 82 will place the piping 78 and 87 in communication so that hydraulic fluid under pressure will be forced into the hydraulic ram 19 to raise the picker mechanism 11 connected thereto. Raising of the picker mechanism will be continued until the uppermost position of the picker mechanism has been reached or until the operating lever 81 is moved to terminate the connection of port 82 with the piping 78 and 87.

If it is now desired to lower the picker mechanism, the operating lever 81 of the section 76 is moved to the left as viewed in Figure 4 and the return piping 91 is placed in communication with the pipe 87 to release the hydraulic fluid under pressure from the hydraulic ram 19 and to permit lowering of the picker mechanism. Lowering continues until the picker mechanism reaches the ground or its lowermost position or until the operating lever 81 is returned to its normal position.

The operation of the section 77 of the dual control valve 74 is similar to that hereinbefore described for section 76.

During the time the manual to automatic control valve 89 is in the position shown, the return line 112 is blocked off from the reservoir 66 and hence hydraulic fluid cannot flow through the right and left hand automatic control valves 33.

Now let it be assumed that it is desired to switch from manual to automatic operation for the raising and lowering of the cotton picker mechanisms. The operating lever 94 is shifted to the right or left as viewed in Figure 4 until the port 96 brings piping 112 and 114 into communication. At the same time, movement of the port 96 to this position interrupts the communication between piping 91 and 92 and therefore prevents the flow of hydraulic fluid through the manual control valve 74.

Now let it be assumed that one of the plant lifters 22 of the right hand picker mechanism encounters a raised portion of ground. The ground will force the plant lifter and the connecting mechanism 56 upwardly to cause rotational movement of the associated arm 53 or 54 and upward movement of the associated member 37 or 38 to cause the operating lever 36 to be actuated to raise the plunger 34 of the automatic control valve 33 for the right hand picker mechanism against the urging of the yieldable spring 63. Upward movement of the member 34 continues until the piping 107 is placed in communication with piping 111 to permit hydraulic fluid under pressure to be introduced into the right hand hydraulic ram 19. This will cause raising of the right hand picker mechanism. Raising of the picker mechanism will cause raising of the automatic control valve 33 mounted thereon. It will be apparent that as the picker mechanism is raised that the relative position of the control valve 33 to the plant lifters will be shifted and for that reason the picker mechanism will only be lifted a distance which will permit it to pass over the raised portion of ground which has been encountered by the plant lifter. As soon as the picker mechanism has been raised this distance, the same relative positions between the plant lifter and the control valve 33 will be established so that the port 103 will be rotated to interrupt the communication between the piping 107 and the piping 111 connected to the hydraulic ram 19.

It will be noted that the hydraulic fluid under pressure which actuates the automatic control valve 33 for the right hand picker mechanism must first flow through the automatic control valve 33 for the left hand picker mechanism. Thus the fluid flows from the pump 68 through the piping 108, through port 105 and into piping 107. It has been found that this piping arrangement greatly simplifies the control as hereinafter explained.

If the same plant lifter were to encounter a depression in the ground, the plunger 34 of the control valve would be lowered and the port 104 would place return piping 112 in communication with the piping 111 to permit fluid to flow from the hydraulic ram 19 into the reservoir 92 through the port 96 and piping 114. As the fluid is released from the hydraulic ram 19, because of the weight of the picker mechanism, the picker mechanism will drop. This action continues until the flow of fluid from the hydraulic ram is interrupted by movement of the port 104 to interrupt the communication between piping 111 and piping 112 or until the picker mechanism touches the ground or reaches its lowermost position.

It will be noted that both the plant lifters 22 and 23 for each picker mechanism can control the automatic control valve 33. The arrangement is such that the plant lifter which is highest in elevation at any particular moment controls the position of the valve 33. Thus, if one of the plant lifters should happen to drop a slight distance below the other plant lifter, the control valve 33 will not be actuated until the other plant lifter also drops. This is because the operating lever 36 for the valve engages both of the members 37 and 38 which are connected to the plant lifters. This has not been found to be objectionable because the plant lifters are relatively close together and for that reason the ground encountered by the plant lifters is of generally the same elevation.

It also will be noted that both of the picker mechanisms cannot be raised or lowered simultaneously because the high pressure fluid for actuating the right hand picker mechanism must flow through the automatic control valve for the left hand picker mechanism. This has not been found to be objectionable because the flow of high pressure fluid to the control valve 33 for the right hand picker mechanism is only cut off during the time when the left hand picker mechanism is being raised or lowered by the automatic control valve 33. Since this raising and lowering generally occurs very rapidly, the flow of high pres-

sure fluid to the right hand picker mechanism is only cut off for a short period of time.

The spring 63 on each of the picker mechanisms is adjusted so that the plant lifters 22 and 23 are normally urged downwardly. This ensures that the plant lifters are always being in engagement with the ground. The valves 33 are normally in the neutral position shown and are only operated when the plant lifters move upwardly or downwardly with respect to the picker mechanism.

10 When it is desired to return to manual operation, it is only necessary to operate the manual to automatic control valve 89 which places piping 91 and 92 in communication.

15 It is apparent from the foregoing that I have provided a new and improved picker mechanism positioning means. Although the automatic positioning means has been shown for use with a two row cotton picker, it is clear that with minor modifications the control system can also be utilized with single row as well as two row cotton pickers. For example, the piping 107 for the left hand control valve 33 can be connected directly to the control valve 89 at the point where piping 112 is attached, and the connections to the other control valve 33 could be eliminated. The connections to the second section 25 77 of the dual control valve 74 could also be eliminated and a single control valve substituted therefor to provide a system which would be adapted for a single row cotton picker.

20 Although my automatic adjusting means has been described in conjunction with single acting hydraulic rams, double acting hydraulic rams may be utilized if desired.

25 It is also apparent from the foregoing that I have provided automatic control means which is rapid and positive operation and which does not interfere with the conventional control provided. The automatic control means can be readily adjusted and will stay in adjustment.

30 I claim:

35 1. In automatic positioning means for a cotton picker, a vertically adjustable picker mechanism, a hydraulic 40 ram connected to said picker mechanism, means providing a source of hydraulic fluid under pressure, manually operated control valve means connected to said source of hydraulic fluid and to said hydraulic ram, a pair of ground traversing shields mounted on said picker mechanism for vertical movement with respect to said picker mechanism, automatic control valve means mounted on said picker mechanism for movement with the picker mechanism, and connected to said means providing a source of hydraulic fluid and to said hydraulic ram, a mechanical linkage connecting said automatic control valve means to at least one of said ground traversing shields so that as said one ground traversing means is moved vertically, said hydraulic ram will be operated to cause raising and lowering of said picker mechanism and manual to automatic control valve means connected to said manually operated control valve means for selecting whether said picker mechanism may be raised or lowered by said manually operated control valve means or by said automatic control valve means.

45 2. In automatic positioning means for a cotton picker, first and second vertically adjustable picker mechanisms, a hydraulic ram connected to each of said picker mechanisms, means providing a source of hydraulic fluid under pressure, valve means mounted on each of said picker mechanisms for movement with the picker mechanisms and connected to said means providing a source of hydraulic fluid, means connecting the valve means mounted on each picker mechanism to the associated hydraulic ram, a pair of ground traversing shields mounted

50 55 60 65 70 75 on each of the picker mechanisms for vertical movement with respect to the picker mechanism and a mechanical linkage connecting at least one ground traversing shield of each picker mechanism to the associated valve means to cause operation of the associated valve means and to thereby actuate the associated hydraulic ram to raise

and lower the associated picker mechanism in response to vertical movement of said one ground traversing shield.

3. Automatic positioning means as in claim 2 wherein in the hydraulic fluid under pressure applied to the valve means for the second picker mechanism first passes through the valve means for the first picker mechanism.

4. In automatic positioning means for a cotton picker, first and second vertically adjustable picker mechanisms, a hydraulic ram connected to each of said picker mechanisms, means providing a source of hydraulic fluid under pressure, manually operated valve control means connected to said source of hydraulic fluid and to said hydraulic rams, ground traversing means mounted on each of said picker mechanism for vertical movement with respect to said picker mechanisms, automatic control valve means mounted on each of said picker mechanisms for movement with the picker mechanisms, means connecting each of said automatic control valve means to said means providing a source of hydraulic fluid and to the associated hydraulic ram, means connecting each of the automatic control valve means to the associated ground traversing means whereby as said ground traversing means is moved vertically, the associated hydraulic ram will be operated to cause raising and lowering of the associated picker mechanism, and manual to automatic control valve means connected to the manually operated control valve means and to each of said automatic control valve means whereby said picker mechanisms may be raised or lowered by said manually operated valve control means or by said automatic valve control means.

5. Automatic positioning means as in claim 4 wherein the automatic control valve means for the second picker

mechanism is connected to the automatic control valve means mounted on the first picker mechanism.

6. In automatic positioning means for a cotton picker, a vertically adjustable picker mechanism, means for adjusting the vertical position of the picker mechanism with respect to the ground comprising a hydraulic ram connected to said picker mechanism, means providing a source of hydraulic fluid under pressure, valve means mounted on said picker mechanism for movement with the picker mechanism and connected to said source of hydraulic fluid and said ram, a pair of ground traversing shields mounted on said picker mechanism for vertical movement with respect to said picker mechanism, means connected to said valve means and to at least one of said shields to operate said valve means and to thereby cause actuation of said ram to raise and lower said picker mechanism in response to vertical movement of the ground traversing means, and additional control valve means connected to the means providing the source of hydraulic fluid and to the ram so that the picker mechanism may be raised and lowered as said additional control valve means is operated, valve means connected to said first named valve and said additional valve means to permit the control of the raising and lowering of said picker mechanism by said first named valve means or said additional valve means.
